(57) **CLAIM**

The ornamental design for a can shaped automated teller machine, as shown and described.

DESCRIPTION

FIG. 1 is a perspective view of a can shaped automatic teller machine according to this invention;

FIG. 2 is a front view of the automatic teller machine of FIG. 1, shown in a reduced scale;

FIG. 3 is a top view of the automated teller machine shown in FIG. 1;

FIG. 4 is a rear view of the automated teller machine shown in FIG. 1; and,

FIG. 5 is a bottom view of the automated teller machine shown in FIG. 1.
